[57] ABSTRACT

An automatic coupler for railway and other vehicles which includes an outer housing carried by the vehicle and formed of a plurality of welded metal plates, with a spring urged coupling hook mounted therein for horizontal pivotal movement for engagement with the hook of a coupler mounted on an adjacent vehicle. The hook is unlocked by a cam bearing on it and the opposed interengaged hook from the adjacent vehicle, which cam may be operated manually or automatically.

The foregoing abstract is not to be taken as limiting the scope of invention, and in order to understand the full nature and extent of the technical disclosure of this patent, reference must be made to the accompanying drawings and the following detailed description.

CAR COUPLER

BACKGROUND OF THE INVENTION

1. Field of the Invention

This invention relates to an automatic car coupler of the type which includes a housing of welded metal plates carried on a car to be coupled, the housing carrying a hook therein which is actuated by a double acting cam.

2. Description of the Prior Art

Automatic car couplers for use on railway vehicles are in common use on subway cars and are desired on other railway vehicles. The couplings in use rely on an outer housing that is formed as a casting and then machined. Such housings are subject to failure due to inclusions, are very heavy and are quite costly to manufacture. The structure must be durable and positive in operation as well as simple, safe and easy to operate and service, which with the couplers presently available is not attainable. Examples of such couplers are shown in the patent to Cope, U.S. Pat. No. 3,405,811 which illustrates an automatic hook type coupler which has a complicated lever arrangement activating a cam to unlock coupler hooks. The Cope structure lacks the simple manual activation of my invention and utilizes a cast housing.

The U.S. patent to William J. Metzger U.S. Pat. No. 3,693,809, is another example of a hook type of car coupler which uses a lever actuated cam to activate the hook on the opposite coupler for disengagement. No simple double acting cam is shown in Metzger which also has a cast housing.

The apparatus of my invention provides a coupler that does not suffer from the disadvantages of prior structures and has many positive advantages.

SUMMARY OF THE INVENTION

This invention relates to a car coupler which includes 40 a housing carried by a railway vehicle, and fabricated of welded metal plates, which contains a spring biased hook for engagement with an opposed hook carried on an adjacent car with automatic or manual double cam action on the hooks for unlocking, with manual actuation of the cam provided from outside the coupler.

The principal object of the invention is to provide a car coupler that is sturdy and of light weight.

A further object of the invention is to provide a car coupler that can be both automatically and manually actuated.

A further object of the invention is to provide a car coupler that is of simple structure but positive in operation.

Other objects and advantageous features of the invention will be apparent from the description and claims.

DESCRIPTION OF THE DRAWINGS

The nature and characteristic features of the invention will be more readily understood from the following description taken in connection with the accompanying drawings forming part hereof, in which:

FIG. 1 is a side elevational view of the car coupler in accordance with the invention;

FIG. 2 is a vertical transverse sectional view taken approximately on the line 2—2 of FIG. 1

FIG. 3 is an enlarged front elevational view of the apparatus of FIG. 1;

FIG. 4 is a top elevational view of the apparatus of FIG. 2;

5 FIG. 5 is a horizontal sectional view, enlarged, taken approximately on the line 5—5 of FIG. 2;

FIG. 6 is a view similar to FIG. 4 but showing the internal parts in a different position;

FIG. 7 is a horizontal sectional view, enlarged, taken 10 approximately on the line 7—7 of FIG. 2;

FIG. 8 is a view similar to FIG. 6 but showing the internal parts in a different position, and

FIG. 9 is a fragmentary perspective view showing a portion of the apparatus of our invention.

15 It should, of course, be understood that the description and drawings herein are illustrative merely and that various modifications and changes can be made in the structure disclosed without departing from the spirit of the invention.

20 Like numerals refer to like parts throughout the several views.

DESCRIPTION OF THE PREFERRED EMBODIMENT

25 Referring now more particularly to the drawings, the car coupler 10 includes an outer housing 11 which is composed of a plurality of metal plates preferably welded together. The housing 11 of generally rectangular configuration, has an integral swivel joint 12 at the rear thereof which is adapted to receive a horizontal shank pin 14 for connection to a yoke 15 on a railway vehicle 16 in well known manner. The housing 11 includes a front plate 20, side plate walls 22, top plate walls 23, and bottom plate wall 24 in angular relation and secured to each other and to the swivel joint 12 and to the front plate 20 by welding. The plate 20, side walls 22, top wall 23 and bottom wall 24 define a cavity 26.

30 The front plate 20 is provided with cooperating centering pins 21 which project forwardly of the plate and are received in sockets 29 in an opposed plate 20.

The front plate 20 is provided with a rectangular opening 27 therein for access to the cavity 26 and with angularly oriented guide surfaces 28 thereon.

35 Within the cavity 26 a hook 30 is pivotally mounted for horizontal movement by a pivot pin 31 extending through and carried by bearings 33 in the top and bottom walls 23 and 24. The hook 30 is of conventional configuration for connection to like hooks and includes a shank 35 with a head 36 thereon which extends beyond the front plate 20 and at the rear extends inwardly to provide a flat pulling face 37. The head 36 has a rounded nose 38 which tapers forwardly along meeting faces 40 and 41. Face 41 is a contact face and in operation engages and slides along a similar face 41 on a hook 30 on a coupler carried by an adjacent car (not shown) to be engaged.

40 The hook 30 is urged on its pivot pin 31 inwardly toward the center of the cavity 26 and opening 27 for coupling by a leaf spring 43 engaged with a vertical pin 44 on an extension 45 of the hook 30. The spring 43 is coiled around a vertical pin 46 carried in bottom wall 24 and secured to side wall 22 by a bolt 47 and nut 48.

45 The hook 30 along the shank 35 rearwardly of head 36 and intersecting face 37 has an face 50 which is engaged by the face 51 of a hook separating cam 52 when the hook is in centered coupling position. The cam 52

is of triangular configuration with a rounded toe 53 and a rounded heel 54 which can engage the face 50 of hook 30 for unlocking. The toe 53 of cam 52 engages the face 41 of the head 36 of the hook 30 from another coupling in an adjacent car (not shown) for unlocking of the hooks 30.

The cam 52 is pivotally mounted by pin 60 to and between the top and bottom walls 23 and 24. The cam 52 adjacent its heel 54 has a rounded nose 61 which is engaged by a pawl 62 for actuation of the cam 52 which pawl 62 is mounted to shaft 63. The shaft 63 extends upwardly through the bottom wall 24 from a gear box 71 which is mounted to the bottom wall 24 and driven by a fluid operated motor 70 of well known conventional type also mounted to wall 24 with connections (not shown) to a source of fluid under pressure (not shown) for motor actuation.

The shaft 63 extends upwardly through top wall 23 and has an arm 64 secured thereto which arm has a shank 65 and rectangular end portion 66 with a round boss 67 on the bottom secured thereto by a pin 68. The boss 67 is carried between the closed loop arms 71 of an actuator arm 75 which has a handle 76. The actuator arm 75 has a plate 77 on the handle 76 at the bottom which may be engaged with a stop 78 carried on the top wall 23 and is restrained from other than limited sliding movement by a bracket 80.

The actuator arm 75 has the end portion 66 of the arm 64 resting on it and free to move therewith when the shaft 63 is actuated by the gear box 65 to operate the pawl arm 62. The crank 75 is used for manual actuation of the pawl arm 62 and cam 52 by lifting the handle until the plate 77 is freed from engagement with the stop 78 and then pulled outwardly which causes pawl arm 62 to rotate and actuates cam 52 for unlocking hook 30.

A switch 81 is provided for automatic coupling and uncoupling of the electric circuit portion of the apparatus mounted to wall 23 with a cam arm 82 attached 40 thereto extending downwardly therethrough with an end enlargement 84 for engagement with the face 41 of the opposed hook 30 from the car to be coupled.

The switch 81 has lines 83 extending therefrom to the electric coupler boxes 85 which are of conventional type mounted to the plate 20 on each side of opening 27, providing electric circuit connection and disconnection between adjacent cars in well known conventional manner.

The plate 20 on each side and outboard of the boxes 85 is provided with side guides 90 which urge couplers 10 on adjacent cars to be coupled, to a position wherein the hooks 30 are in line for engagement, further alignment being accomplished by centering pins 21, sockets 29, surfaces 28 and the faces 40 on noses 38 of hooks 30 in well known conventional manner.

The mode of operation will now be pointed out.

When coupling is desired adjacent cars are moved together wherein the guides 90 urge the housing 10 to a central position with the hooks 30 being urged into opposite openings 27 by surfaces 28. The faces 41 of hooks 30 slide along each other until they pass the intersection of faces 37 when the action of springs 43 forces the hooks 30 to coupled position and pulling faces 37 into meeting relation. The faces 41 also engage enlargements 84 of cam arms 82 causing the electrical coupler circuits to be joined in well known man-

ner. The pins 21 engage in sockets 29 and the plates 20 on couplers 10 are brought into meeting relation.

When uncoupling is desired the motor 70 for either of the interengaged couplers is activated which through 5 gear box 71 and shaft 63 actuates the pawl 62 to rotate the cam 52. Movement of one of the cams 52 by engagement of heel 54 with face 50 of one hook 30 and of the nose 53 with the face 41 of the other hook 30 forces the hooks 30 apart with attendant disengagement 10 of the faces 37. The cam arm 82 is also released causing the electric circuit to be disconnected. The cars can then be moved apart and the hooks 30 are returned to centered position by the springs 43.

Should manual actuation be necessary due to pneumatic system failure or otherwise this can be effected from either side. The handle 76 located above the housing 10 where it is readily accessible and safer to use is grasped and lifted upwardly to disengage plate 77 from stop 78. The handle 76 is pulled outwardly causing the arm 64 to rotate shaft 63 thereby rotating cam 52 and forcing hooks 30 apart as previously explained. The electric circuits are broken as discussed, the cars are uncoupled and the hooks 30 return to centered position.

The cars can be coupled and uncoupled automatically and manually with the cycles repeated as desired.

It will thus be seen that apparatus has been provided with which the objects of the invention are achieved.

We claim:

- 30 1. Apparatus for controlling the uncoupling of railway vehicles which comprises for each of the vehicles to be coupled
  - a housing at an end of the vehicle to be coupled to another vehicle,
  - said housing having a resiliently biased coupling hook carried therein having a position for coupling engagement and an out of engagement position,
  - said coupling hook having a vertically disposed pulling face and vertically disposed control face,
  - a cam carried in said housing engageable with said control face for moving said coupling hook to an out of engagement position,
  - a pawl in engagement with said cam for actuating said cam, and
  - means for moving said pawl for operating said cam.
2. Apparatus as defined in claim 1 in which said last mentioned means is a motor.
3. Apparatus as defined in claim 2 in which additional manual operating means accessible from one side of the vehicle is provided for operation independently of said motor.
4. Apparatus as defined in claim 1 in which said last mentioned means comprises manual operating means accessible from one side of the vehicle.
5. Apparatus as defined in claim 4 in which said manual operating means comprises an arm and locking means for normally restraining said arm against movement.
6. Apparatus as defined in claim 1 in which said hook has an additional vertically disposed control face for movement of said coupling hook by a cam of an uncoupling apparatus of another vehicle coupled thereto.
7. Apparatus as defined in claim 1 in which said housing is comprised of a plurality of plates welded together.
8. Apparatus as defined in claim 1 in which

said housing has an interior space and comprises a vertical front contact plate through which a coupling hook extends from said interior space,
 said interior space provides for the reception of a coupling hook of another vehicle to be coupled,
 5 9. Apparatus as defined in claim 8 in which aligning members are provided on said front contact plate for engagement with the front contact plate of another vehicle to be coupled.

5

10. Apparatus as defined in claim 3 in which said additional manual operating means comprises members carried on the top of said housing.
 11. Apparatus as defined in claim 4 in which said last mentioned means comprises members carried on the top of said housing.
 12. Apparatus as defined in claim 5 in which said arm is carried on the top of said housing.
